[57] CLAIM

The design of a beverage can holder, as shown and described.

DESCRIPTION

FIG. 1 is a side view of a beverage can holder showing my new design;

FIG. 2 is a top plan view thereof;

FIG. 3 is a cross-sectional view taken along line 3—3 of FIG. 2; and,

FIG. 4 is a front view thereof.

The undisclosed right side view is a mirror image of the left side.

The undisclosed bottom view is unornamented.
